W. ARMSWORTH.
CAP FOR DRAIN TILES.
APPLICATION FILED FEB. 6, 1913.

1,103,391.

Patented July 14, 1914.

UNITED STATES PATENT OFFICE.

WILLIS ARMSWORTH, OF CERRO GORDO, ILLINOIS.

CAP FOR DRAIN-TILES.

1,103,391.

Specification of Letters Patent. Patented July 14, 1914.

Application filed February 6, 1913. Serial No. 746,651.

To all whom it may concern:

Be it known that I, WILLIS ARMSWORTH, a citizen of the United States, residing at Cerro Gordo, in the county of Piatt, State 5 of Illinois, have invented certain new and useful Improvements in Caps for Drain-Tiles; and I do hereby declare the following to be a full, clear, and exact description of the invention, such as will enable others 10 skilled in the art to which it appertains to make and use the same.

The present invention is directed to improvements in caps for drain tiles, and has for its object to so construct a device of this 15 character that it may be readily placed upon the upper end of the tile, and when in place will prevent foreign matter from entering, but will readily permit water to enter the tile.

20 With these and other objects in view, this invention resides in the novel features of construction, formation, combination and arrangement of parts to be hereinafter more fully described, claimed and illustrated in 25 the accompanying drawing, in which:—

Figure 1 is a side elevation of the cap showing it in place upon a tile. Fig. 2 is a vertical sectional view through the same. Fig. 3 is a bottom plan view.

30 Referring to the drawing, the numeral 1 designates a section of tile, which is connected to a sewer pipe in any suitable manner. In this instance the tile 1 is shown as formed from cement, but it will be of course 35 understood that the same may be made from any other material as well as the cap 2.

The cap 2 comprises a circular plate 3 having depending therefrom an annular marginal flange 4, which is adapted, when 40 the cap is upon the tile 1 to have its lower edge positioned below the upper edge of the tile 1. The diameter of the plate 3 is such that the inner surface of the flange 4 is spaced from the upper side of the tile 1 so

45 that water may freely pass through the space when entering the tile. The under surface of the plate 3 is provided with a plurality of radially arranged elongated lugs 5, which have their inner ends spaced 50 apart, and are adapted to rest upon the

upper edge of the tile 1. By arranging the lugs 5 radially water passages 6 are provided, so that when said lugs are resting upon the upper end of the tile 1 the water may pass through the passages 6 to the tile. 55

The vertical dimensions of the lugs 5 are less than the similar dimension of the flange 4, thus when the cap 1 is in place, the lower edge of said flange will be below the upper edge of the tile 1. 60

From this construction it will be seen that a cap has been provided which can be readily applied or removed from the drain tile, and one which is exceedingly simple in construction and may be manufactured at a 65 minimum cost.

The plate 3 is provided with a plurality of openings 7, which serve to thoroughly ventilate the cap.

What is claimed is:—

1. A cap for drain tiles comprising a plate having depending therefrom a vertical marginal flange, a plurality of radially arranged elongated lugs formed integral with the under surface of the plate so as to provide 75 passages, said lugs being adapted to rest upon the upper end of the drain tile, so that the lower edge of the flange will be below the upper edge of the drain tile, the diameter of said plate being such that said flange will 80 be spaced from the side of the tile, as and for the purpose set forth.

2. A cap for drain tiles comprising a plate having depending therefrom a vertical annular flange, a plurality of radially arranged elongated lugs formed integral with the under surface of the plate so as to provide 85 passages, said lugs being adapted to rest upon the upper end of the drain tile, so that the lower edge of the flange will be below the upper edge of the drain tile, the diameter of the plate being such that said flange will be spaced from the side of the tile. 90

In testimony whereof I affix my signature 95 in the presence of two witnesses.

WILLIS ARMSWORTH.
